AUDIO REPRODUCTION UNIT

George E. Lyall, Melrose, Mass., assignor to
Automatic Radio Mfg. Co., Inc.

Filed Sept. 5, 1972, Ser. No. 286,273

Term of patent 14 years

Int. Cl. D14—03

U.S. Cl. D26—14 B

Fig. 1.

Fig. 2.

FIG. 1 is a perspective view of an audio reproduction unit, showing my new design;

FIG. 2 is a side view thereof;

FIG. 3 is a rear view thereof; and

FIG. 4 is a bottom view thereof.

I claim:

The ornamental design for an audio reproduction unit, substantially as shown and described.
